WARM AIR REGISTER

Orie A. Fender, Millwood, Wash.

Application April 18, 1958, Serial No. 729,316

6 Claims. (Cl. 98—40)

My invention relates to improvements in a warm air register. It is adapted especially to control the inlet of warm air into a room along the perimeter of the floor. The use of warm air inlets along the junction of the floor with the side wall of a room is advantageous for many reasons. One of the problems with registers of this type is control of the air flow through the register outlet. It is the purpose of my invention to provide a register with simple, strong and durable mechanism for maintaining an outlet from the hot air inlet into the room of the desired size or closing the outlet entirely.

The nature and advantages of my invention will appear more fully from the following description and the accompanying drawings. It should be understood, however, that the drawings and description are illustrative only and are not intended to limit the invention except insofar as it is limited by the claims.

In the drawings:

Figure 1 is a view in front elevation of a warm air register embodying my invention;

Figure 2 is a longitudinal sectional view in a vertical plane through the register;

Figures 3 and 4 are enlarged sectional views taken on the line 3—3 of Figure 1, showing two positions of the damper;

Figure 5 is a fragmentary perspective view of the register on an enlarged scale with parts broken away to illustrate the construction; and

Figure 6 is a detailed sectional view illustrating a slight modification.

Referring now to the drawings, the warm air register embodying my invention comprises an elongated shell adapted to fit over a warm air inlet to a room through the floor of the room at the side wall thereof. The shell has a back panel 10 adapted to rest against the side wall of a room in the position usually occupied by the base board. The panel 10 has a top ledge 11 bent forward and provided with a down turned flange 12. At the ends of the back panel 10 there are end plates 13 and 14 that have right angular flanges 15 and 16 at their back edges that fit inside the back panel and are secured thereto as by spot welding or other means. Bottom channels 17 and 18 have their ends flush with the ends of the panel 10 and extend along the panel 10 part way toward the center to leave a bottom opening between their inner ends, 19 and 20. The channels 17 and 18 have their rear flanges 21 and 22 extending upward inside the back panel 10 and affixed thereto by spot welding or other means. The end plates 13 and 14 have bottom flanges 23 and 24 overlapped with the bottom channels 17 and 18 and affixed thereto.

The front of the register is composed of a preformed sheet member 25 and a deflector plate 26 affixed thereto by spot welding or other means. Each of the end plates 13 and 14 has a front flange 29 to which the sheet member 25 is fastened by a screw 30. The member 25 has a floor engaging flange 31 thereon extending forwardly from its lower edge. The deflector plate 26 has its lower por-

2

tion 26a bent away from the member 25 to receive the front flanges 27 and 28 of the channels 17 and 18. The ends of the deflector plate 26 are cut off shorter than the ends of the member 25 so that they do not overlap the front flanges 29 of the end plates 13 and 14. The top of the member 25 is folded over to provide a smooth rounded edge 32 and to give added strength along this edge which is an edge of the outlet opening of the register. It will be observed from Figures 3 and 4 that the member 25 is bent along three lines that run the length of the member 25. These bends provide the horizontal floor engaging flange 31, a vertical portion extending up from the flange and carrying the deflector plate 26, a rearwardly inclined intermediate portion and the folded over top portion which is further inclined rearwardly. In addition to providing the register with a pleasing front surface, this construction provides adequate strength in the member 25 to withstand the wear and tear of everyday use in a home.

The construction thus far described comprises a register shell which is provided with a bottom inlet opening of the full width of the shell, but closed off at its ends by channels which support the shell on a floor. The shell also has an upper outlet opening extending the length of the shell but spaced forwardly from the back panel and in a plane 25 angularly disposed to the vertical to direct air out into a room in which it is installed at a distance from the room wall against which the back panel is placed. My invention includes a damper 33 in the register which acts to regulate the area of the outlet opening and as a baffle 30 cooperating with the deflector plate to direct the warm air away from the back panel to the outlet opening.

The damper 33 is a plate which extends full length of the register. It has a rearwardly directed top section 34 fitting closely to the depending flange 12 on the top ledge 11 of the back panel 10. A finger piece 35 is provided on the damper 33. The damper 33 is bent slightly at 36 along a line that extends the length of the damper to stiffen it and has a flange 37 at its lower edge bent down and forward to extend toward the front of the register at an angle of about 45 degrees to the damper itself. This forms a V-shaped nose 38 at the lower edge of the damper 33 which nose bears against the back panel 10 and the back flanges 15 and 16 of the end panels 13 and 14.

45 The nose 38 is yieldingly pressed toward the back panel and the damper 33 is supported to keep the top section 34 up against the flange 12 by a strip 40. The strip 40 is struck out of the back panel 10 as illustrated in Figures 3 and 4, or it is a separate strip 40', spot welded or otherwise affixed to the back panel 10 as illustrated in Figure 6. This strip 40 or 40' has a right angular lip 41 along its top edge behind which the flange 37 of the damper 33 hooks. In all positions of the damper 33 the flange 37 makes an angle of less than 90 degrees with the strip 40 55 so that the tendency of strip 40 is to force the flange 37 upward against the lip 41.

The strip 40 and the back panel 10 are of sheet metal having sufficient resilience to yield enough to allow one to move the damper 33 between the positions illustrated 60 in Figures 3 and 4. Also the frictional engagement of the nose 38 with the panel 10 and the flanges 15 and 16 is enough to hold the damper in any position to which it is adjusted between these two limiting positions.

It is believed to be clear from the foregoing description and the drawings that the register constructed in accordance with my invention provides a simple durable mechanism for controlling the flow of warm air through it into the room in which it is installed. It also is readily cleaned by removing the front member 25 after which the damper 33 can be swung down until it is easy to separate the flange 37 from the lip 41. All of the mechanism is

made of sheet metal which is be readily protected against rust and corrosion. The exterior can be painted or decorated without in any way affecting the operation of the damper.

Having described my invention, I claim:

1. A warm air register shell having an inlet opening and an outlet opening, said shell having a back panel, and having a top ledge having a downwardly directed front edge spaced from the back panel, said register shell having a front wall member, the upper edge of which is spaced below said front edge of the top ledge to provide the outlet opening end plates to which said front wall member and said back panel are secured to complete the shell, a damper plate mounted on the back panel and extending upwardly and forwardly from the back panel into said outlet opening, said damper plate having a rearwardly directed top section adjacent to the front edge of the top ledge being sufficiently wide to extend beyond said front edge when said damper is in closed position, the damper plate having a flange at its lower edge extending forwardly away from the back panel, a supporting strip on the back panel extending forwardly and upwardly therefrom to provide yielding support for said lower flange, and a lip on said strip extending toward the back panel to provide a recess in which the lower flange on the damper plate seats.

2. A warm air register shell having an inlet opening and an outlet opening, said shell having a back panel, and having a top ledge having a downwardly directed front edge, spaced from the back panel, said register shell having a front wall member, the upper edge of which is spaced below said front edge of the top ledge to provide the outlet opening, end plates to which said front wall member and said back panel are secured to complete the shell, a damper plate mounted on the back panel and extending upwardly and forwardly from the back panel into said outlet opening, the damper plate having a flange at its lower edge extending forwardly away from the back panel, a supporting strip on the back panel extending forwardly and upwardly therefrom, said strip yieldingly pressing against said flange and holding the lower

edge of the damper plate against the back panel and a lip on said strip extending toward the back panel to provide a recess in which the lower flange on the damper plate seats.

5. The invention defined in claim 2 wherein the supporting strip is struck out of the back panel.
6. The invention defined in claim 2 wherein the supporting strip is a separate piece but affixed to the back panel.
7. The invention defined in claim 2 wherein the front wall member has a deflector plate affixed thereto within the shell and diverging upwardly from the front wall member toward said damper plate.
8. A warm air register shell having an inlet opening and an outlet opening, said shell having a back panel having a top ledge extending forwardly therefrom and having a depending front flange, a front wall member spaced from the back panel, end plates to which said front wall member and said back panel are secured to complete the shell, the top edge of the member being spaced below the top ledge flange to provide the outlet opening, a damper plate mounted on the back panel and extending upwardly and forwardly into said opening, said plate having a rearwardly directed top section adjacent to said depending flange, the damper plate having a flange at its lower edge extending forwardly away from the back panel, a supporting strip on the back panel extending forwardly and upwardly from the plane of the back panel to provide yielding support for said lower flange and a lip on said strip extending upwardly and rearwardly therefrom behind which lip the lower flange on the damper plate hooks.
